United States Patent Office

Des. 206,490
Patented Dec. 20, 1966

206,490

CAN OPENER

Claude A. Young, 126 N. Kensington St.,
La Grange, Ill. 60525

Filed Jan. 26, 1966, Ser. No. 773

Term of patent 14 years

(Cl. D55—1)

Fig. 3.

FIGURE 1 is a front perspective view of a can opener, showing my new design;

FIGURE 2 is a front elevational view of the can opener;

FIGURE 3 is a rear perspective view of the can opener; and

FIGURE 4 is a rear elevational view of the can opener.

The dominant features of my design reside in the features shown in full lines.

I claim:

The ornamental design for a can opener, substantially as shown and described.
